R. R. COES.
HANDLE FOR WRENCHES.
APPLICATION FILED MAY 1, 1919.

1,311,111.

Patented July 22, 1919.

Inventor.

Russell R. Coes,
By Chas. H. Burleigh
Attorney.

UNITED STATES PATENT OFFICE.

RUSSELL R. COES, OF WORCESTER, MASSACHUSETTS, ASSIGNOR OF ONE-HALF TO COES WRENCH CO., OF WORCESTER, MASSACHUSETTS, A CORPORATION OF MASSACHUSETTS.

HANDLE FOR WRENCHES.

1,311,111.

Specification of Letters Patent.

Patented July 22, 1919.

Application filed May 1, 1919. Serial No. 294,045.

To all whom it may concern:

Be it known that I, RUSSELL R. COES, a citizen of the United States, residing at Worcester, in the county of Worcester and State 5 of Massachusetts, have invented certain new and Improved Handles for Wrenches, of which the following is a specification.

This invention relates to a novel construction for metal wrench handles, and more 10 particularly to the manner and means for internally supporting the tubular shell or hollow grip portion of the handle in connection with the handle-frame and wrench-bar shank, as more fully hereinafter explained; 15 the object being to provide a construction that can be economically manufactured, and which shall be efficient, strong and durable for use.

I attain these objects by a wrench-handle 20 embodying the peculiar construction illustrated by the accompanying drawing, wherein Figure 1 represents a side view of my improved wrench-handle, the exterior shell being shown in section. Fig. 2 represents a 25 central longitudinal section at line V V on Fig. 1. Fig. 3 represents a side view of the tip end member separately. Fig. 4 is a transverse section at line Z Z on Fig. 3. Fig. 5 is a transverse section at line W W 30 on Fig. 1. Fig. 6 is a transverse section at line X X on Fig. 1, with the exterior tubular member omitted, and Fig. 7 is a transverse section at line Y Y on Fig. 1.

Referring to the drawing, numeral 1 indicates the wrench-bar and 2 the wrench-bar-shank, formed with parallel transversely rounded edges as heretofore practised. 35 H indicates the cast metal handle-frame composed of the neck-supporting ferrule 3, having the reduced end and shoulder 5, the integrally attached longitudinal edge-embracing members 6 extending parallel with each other along the rounded edges of the shank 2, and connected, near their upper part 40 across the bar space, by integrally formed tie-plates 7; the lower ends of said edge-embracing members being unconnected with each other, but notched on their outer corners 8.

45 10 indicates the exterior grip-member consisting of a hollow tubular shell of comparatively thin pipe or metal of uniform thick-

ness, and of a length to fill the distance between the shoulder 5 at the inner end of the ferrule and the end tip of the handle. 55

The edge embracing members 6 may be reduced along their outer corners, as indicated at 6⁺; their outwardly facing edges being formed to match the interior surface of the shell 10. 60

Upon the cross-plate 7, at each side of the shank, I provide narrow outwardly projecting brace lugs 9, the outer ends of which fit against the inner surface of the tubular shell for supporting the same, in the manner 65 shown in Figs. 2 and 5. The handle-frame is secured upon the shank by a key or pin 16 inserted through the parts as indicated. 70

In accordance with my invention the tip or end member 12 is provided with longitudinally projecting tongues 13, having a space 14 between them equal to the flatwise thickness of the bar-shank. Said tongues are edgewise disposed to fit the space between the shank and inner surface of the 75 shell, and extend longitudinally along the sides of the shank nearly to the pin, 16, or approximately about half the length of the shell, see Fig. 1. The tip 12 is formed with a circumferential reduced portion 17 that 80 fits within the end of the tubular member; and with a shoulder 15 against which the end of said tubular member abuts when the parts are in position. 85

When assembling the parts of the wrench 90 the handle-frame H is slipped endwise onto the wrench-bar shank 2; its inner surfaces fitting snugly against the edges and sides thereof. The external tubular grip-member 10 is next slipped over the handle-frame and 95 brace members 9, bringing its end onto the reduced part of the ferrule and against the shoulder 5. The tip 12 is then assembled by introducing the tongues 13 into the spaces between the shank 2 and tubular member 10 95 and driving it up until the reduced portion 17 enters and the shoulder 5 abuts firmly against the end of the tube. The end of the shank is then riveted at the outside of the tip to permanently unite the parts. 100

This improved construction produces an efficiently strong wrench handle of comparatively light weight; one which is simple, economical and convenient for manufacture,

since the several operations for fitting and assembling the parts can be readily performed, chiefly by machinery, and requiring but a small amount of labor.

5. What I claim and desire to secure by Letters Patent, is—

1. In a wrench handle the combination with the wrench-bar shank having straight side surfaces, and a grip-forming shell consisting of uniform straight drawn tubing, of a tip-end member provided with a plurality of integral longitudinal tongues that extend into the interior of the handle, the inner faces of said tongues contacting with the 10 sides of the wrench-bar-shank and their outer faces contacting with the interior of said grip-forming tube, substantially as and for the purpose set forth.
2. In a wrench-handle, in combination, a 20 wrench-bar-shank, a metal handle-frame consisting of a neck-supporting ferrule with integrally formed edge-embracing members extending longitudinally therefrom, integrally united by cross-plates having outwardly projecting brace lugs thereon, an external tubular grip-member having longitudinally straight inner surfaces, and a tip- 25

end member provided with longitudinally projecting tongues arranged on its inner face and extending within the tubular grip-member, with their inner and outer edges respectively seated against the surface of the shank and the interior of the tubular grip member.

3. A handle for screw wrenches, comprising a comparatively thin straight tubular metal shell of approximately uniform thickness, a handle frame including a neck-supporting ferrule with integrally attached longitudinal shank-embracing edge-members, 40 cross-plates integrally uniting said edge members near their upper ends, laterally outstanding lugs upon said cross-plates, a tip-end member provided with edgewise-disposed longitudinal tongues that extend 45 into the tubular shell for approximately one-half its length, the space between said tongues equaling the thickness of the bar-shank, and the combined breadth of said tongues and space equaling the inner diameter of the tubular shell.

Witness my hand this thirtieth day of April, 1919.

RUSSELL R. COES.
